UNITED STATES PATENT OFFICE

WILLIAM STANLY, JR., AND JOHN F. KELLY, OF PITTSFIELD, MASSACHUSETTS, ASSIGNORS TO THE STANLEY LABORATORY COMPANY, OF SAME PLACE.

ALTERNATING-CURRENT GENERATOR.

SPECIFICATION forming part of Letters Patent No. 499,446, dated June 13, 1893.

Application filed January 9, 1893. Serial No. 457,707. (No model.)

To all whom it may concern:

Be it known that we, WILLIAM STANLY, Jr., and JOHN F. KELLY, citizens of the United States, residing at Pittsfield, in the county of 5 Berkshire and State of Massachusetts, have invented certain new and useful Improvements in Alternating-Current Generators, of which the following is a specification, reference being had to the drawings accompanying and 10 forming a part of the same.

Our present invention is an improvement in alternating current generators, and has for its objects to provide a better and more economical mechanical construction of such machines and to increase their effective out-put. 15

We have illustrated our invention as applied to a well understood type of machine designed to produce two currents of differing phase, but the applicability of the improvements to the ordinary or single circuit generators is obvious.

In the accompanying drawings Figure 1 is a central vertical longitudinal section of our improved alternator. Fig. 2 is an end view 25 of the same with a portion of the end plate or frame removed.

One portion of the machine is composed of two annular castings A fitted together. To opposite sides of these are clamped the circular end plates B B by bolts C, that serve 30 also to bind together the two parts or sections of the ring. These parts constitute the stationary frame for the machine, and are suitably mounted on supports D D, forming 35 part of the annular castings.

The end plates B B are formed with suitable journal boxes E, in which are the bearings of any proper description for a shaft F that carries an iron or steel core G, that 40 constitutes the rotary element of the machine.

To the outer or sectional ring A are secured two polar extensions H H, composed of thin annular plates constituting laminated rings and bound together by bolts or other suitable 45 means.

The core G is provided with polar extensions K which are preferably laminated. These polar extensions may be wider than shown, even to the extent of forming ribs 50 across the core G, and it is also obvious that,

to a certain extent, the core G serves merely as a carrier or such a support as an ordinary spider, but it may be observed that the use of a spider would be objectionable on account of a greater magnetic leakage.

L is the energizing coil. This may be placed either between the polar extensions K, in which case sliding contacts would be required to maintain it in circuit, or in a recess provided for it in the annulus A between the polar extensions H. The effect of this coil is to establish a magnetic circuit through the polar extensions H, K, and through the intermediate portions of the annulus A and cylinder G, respectively, and across air spaces between the 65 laminated rings H and K.

In the rings H are transverse recesses for the reception of the induced coils P, S, while the plates of the rings K are stamped or punched out in such shape that when assembled they will present a series of poles, the width of the faces of which is about equal to the distance between the centers of any two adjacent recesses in the ring H, which contain the coils of one circuit, so that in the 70 present machine, which has two induced circuits in quadrature, the poles of the rotating element, when just approaching or leaving the coils of one circuit, are central with respect to the coils of the other.

Under the conditions secured by the above described constructions, and when the machine is in operation, the coil L being connected with a source of continuous current and the coils P, S, being connected up in the 75 usual manner, there will be a variation in the magnetic field or lines of force through the coils P, S, but there will be no change of flux in the magnetic circuit. In order that the magnetic variations that produce the currents may not be too abrupt, and so that the waves of the two currents may have the sinusoidal form which is the most desirable in practice, the faces of the poles K instead of being concentric with the faces of the outer 80 ring H approximate in form the inverse of a sinusoidal curve.

This varies the clearance between the two polar faces and generates currents of more gradually rising and falling 95 potential.

100

It will be observed that the generator described is not only compact but is mechanically designed with a view of obtaining the greatest possible simplicity in construction and design. All the parts may be cast or punched out and finished in an ordinary lathe. It thus becomes an easy matter to center all the parts.

What we claim is—

- 10 1. In an alternating current generator, the combination of a rotary core or support having outwardly projecting poles, a stationary magnetic annulus having corresponding and inwardly projecting polar extensions, an energizing coil secured between the polar extensions, and stationary induced coils, portions of which are contained in transverse recesses in the said polar extensions, as set forth.
- 15 2. In an alternating current generator, the combination with a rotary magnetic core, and laminated rings formed with polar projections secured to the same, of a surrounding stationary annular casting, laminated rings secured to its inner face in positions corresponding to those on the rotary cylinder, an energizing coil in a space between the laminated

rings, and induced coils applied or secured to said rings and passing through transverse recesses in the face of the same, as set forth.

3. The combination with the stationary annular magnetic element or part of the generator, the induced coils on the polar extensions H, and the energizing coil between such extensions, of the rotary core having two corresponding rows of poles K, the faces of which are cut down so that their clearance is increased from their centers to their edges or sides.

4. In an alternating current generator, the combination with an annular core, and a concentrically mounted cylindrical core with radiating poles at the ends, of an energizing coil in a central circumferential recess in the inner face of the annular core, and induced coils exposed to the variations of magnetic strength caused by the rotation of the cylindrical core, as set forth.
